VENTED TANK CAP

Lowell J. Smith, Connersville, Ind., assignor to
Stant Manufacturing Company, Connersville,
Ind., a corporation of Indiana

Application November 1, 1947, Serial No. 783,506

6 Claims. (Cl. 220—44)

1

The present invention relates to a vented closure cap for automobile gasoline tanks, or the like, and the primary object of the invention is to provide an improved cap structure which, while providing for desired venting of the container with which the cap is associated, eliminates any manufacturing expense in the provision of such venting. So far as I am advised, previously known structures intended to provide suitable venting means in closure caps have invariably required special manufacturing operations, such as drilling, punching, spinning, or the like. According to the present invention, the venting means is provided in the same stamping operations which form the elements which are to be assembled to produce a finished closure cap, otherwise of substantially standard construction. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a top plan view of a cap constructed in accordance with the present invention;

Fig. 2 is a bottom plan view thereof; and

Fig. 3 is an enlarged section taken substantially in the planes indicated by the section line 3—3 of Figure 1, and showing the cap associated with a fragment of a filler neck of standard construction, the cap being not quite seated on said neck.

In one well known form of closure cap, a body element 10, formed of sheet metal or the like, is provided with a central depressed region 11 centrally perforated at 12; and a securing element 13, likewise formed of sheet metal or the like, centrally provided with a dome 14 centrally perforated as at 15, is secured to the body member by means of a rivet 16 passing through the registering openings 12 and 15 and headed over at both ends as at 17 and 18. The securing member 13 is formed to provide an annular region 19 disposed in spaced facing relation to the central portion 11 of the body 10, and immediately surrounding the peripheral wall 20 of the dome 14. The member 13 has a depending annular skirt 21 formed, at two or more peripherally spaced points, with radial projections 22 adapted to pass through notches formed in a filler neck 24 and then to co-operate with cam surfaces 23 on said neck to draw a washer 25 into coopera-

tive engagement with said neck. The washer 25 surrounds the dome wall 20 and is pressed against the region 19 of the securing member 13 by means of an annular spring 26 confined between the washer 25 and a washer 27 which, in turn, bears against that area of the body 10 which faces the region 19 of the securing member. This arrangement, of course, provides, when the cap is turned down tightly upon the filler neck, a reasonably fluid-tight seal for the open mouth of the filler neck. In some forms of cap assemblies, the washer 25 may snugly engage the dome wall 20, while in other forms there may be a substantial clearance therebetween.

Such a construction is satisfactory for use in connection with certain containers which do not require to be vented, or with containers which are provided with independent venting means. But most automobile gasoline tanks, which must be vented for safety and to permit the entrance of air into the fuel tank in order to replace the fuel as it is used from the tank, are without independent venting means and must be vented through the filler neck closure cap. One well known difficulty encountered with vented caps when used on automobiles or tractors or other vehicles causing violent agitation of the fuel within the tank is loss of fuel out through the vent during surging of the fuel. While numerous expedients for thus venting gasoline tanks through filler caps have been known heretofore, I have devised a novel means to provide for the necessary venting, while guarding against loss of fuel through the venting passages.

As is clearly illustrated in the drawings, the metal of the securing member is displaced or distorted to provide an offset, substantially radial passage 28 extending from a point radially outside the region of engagement between the washer 25 and the annular area 19 to intersect with an axial passage 29 formed by displacing or offsetting the metal of the dome wall 20, and leading into the region above the washer 25. Preferably, the metal of the securing member 13 is thus offset at two or more peripherally spaced points, and I have shown venting passages 28 and 29 at two diametrically opposed points.

Likewise, the metal of the body member 10 is similarly offset or distorted to provide a passage 30 leading radially from the region inside the washer 27 to the region outside said washer. Again, I have shown two such passages at diametrically spaced points. Preferably, but not necessarily, the passages 30 will be peripherally spaced from the passages 28 and 29; and I have

shown them ninety degrees removed. Such peripheral spacing restricts the discharge of hot steam or spray from the container, when that container is an automobile radiator or the like, and substantially guards against the loss of fuel when fuel is surging violently when the cap is associated with the gasoline tank. Thus by varying the number of passages, the peripheral spacing thereof, and the depth or size thereof, I am able accurately to control the venting action of the closure to adapt it to specific requirements.

It will be clear that the provision of the simple offset passages in the elements 10 and 13 may be easily accomplished by the same stamping dies which form those elements from sheet metal, and at no manufacturing cost, once the dies have been produced.

I claim as my invention:

1. A closure cap comprising a body member, an element centrally secured to said body member and axially spaced therefrom near its periphery, and annular washer means positioned between said body member and the axially-spaced portion of said element, and bearing against facing annular areas of said body member and said element, each of said areas being provided with an offset region displaced from the general plane of such area out of engagement with said washer means and extending from a point radially inward from said washer means to a point radially outward from said washer means to provide venting passages between said washer means and said element and between said washer means and said body member.

2. A closure cap comprising a disc-like body member having a down-turned peripheral flange, a securing element having a central dome centrally secured to the under surface of said body member, said dome being surrounded, near its base, by an annular region spaced from said body member, and said securing element being pro-

vided with means for securing engagement with a container mouth, and washer means cooperatively surrounding the periphery of said dome and bearing against the annular region of said securing element and against the region of said body member facing said annular region, the material of said securing element being offset in said annular region and in the periphery of said dome to provide a vent passage past said washer means, and the material of said body member being offset in said facing region to provide a vent passage past said washer means.

3. The cap of claim 2 in which the material of said securing element is offset at two peripherally-spaced locations and the material of said body member is offset at two peripherally-spaced locations to provide such vent passages.

4. The cap of claim 3 in which said offset locations of said securing element are diametrically opposed and the offset locations of said body member are diametrically opposed.

5. The cap of claim 3 in which the offset locations of said body member are peripherally spaced from the offset locations of said securing element.

6. The cap of claim 4 in which the offset locations of said securing element are 90° removed from the offset locations of said body member.
